UNITED STATES PATENT OFFICE.

STEPHEN A. VAIL, OF PHILADELPHIA, PENNSYLVANIA, ASSIGNOR TO VAIL BROS., A FIRM COMPOSED OF ARAUNA M. VAIL AND STEPHEN A. VAIL, OF PHILADELPHIA, PENNSYLVANIA.

DESIGN FOR A CANDY, PERFUMERY, SOAP, OR TOILET-ARTICLES BOX.

43,583.

Specification for Design.

Patented Feb. 18, 1913.

Application filed November 6, 1912. Serial No. 729,909. Term of patent 3½ years.

To all whom it may concern:

Be it known that I, STEPHEN A. VAIL, a citizen of the United States, residing in the city and county of Philadelphia, State of Pennsylvania, have invented a new, original, and ornamental Design for a Candy, Perfumery, Soap, or Toilet-Articles Box, of which the following is a specification, reference being had to the accompanying drawing, forming part thereof.

Figures 1 and 2 are perspective views of a box showing my new design. Fig. 3 is a bottom plan view thereof.

I claim:

The ornamental design for a candy, perfumery, soap, or toilet-articles box, as shown.

STEPHEN A. VAIL.
